ROTARY DEVELOPING TANK

Sydney S. Alberts and Arthur S. Alberts,
Yonkers, N. Y.

Application April 11, 1946, Serial No. 661,404

12 Claims. (Cl. 95—90.5)

1

This invention relates to apparatus for processing photographic materials and relates more particularly to an improved processing tank for photographic negatives.

The primary object of the invention is to provide a negative processing apparatus in which the undeveloped negative can be placed and from which it need not be removed until all the various steps of developing, treatment with stop and fixing baths, and washing are completed.

Another object of the invention is to provide a negative processing tank in which the agitation of the negative in the bath is wholly automatic, thereby eliminating the necessity for manual agitation or manipulation.

Another object of the invention is to provide a negative processing apparatus which will accomplish a more thorough agitation of the negative in the bath.

Another object of the invention is to provide a negative processing apparatus which facilitates the maintaining of a uniform temperature of the bath.

A further object of the invention is to provide a negative processing apparatus or tank which can be conveniently manipulated with a minimum loss of time between the application of the successive treatment baths.

The invention will be understood from a consideration of the accompanying drawings in which apparatus for the treatment of roll or strip film is illustrated in a number of different embodiments, although it will be understood that the apparatus is susceptible of use for the treatment of flat negatives merely by an appropriate change in the construction of the negative holder. In these drawings:

Fig. 1 is a view in vertical section taken centrally and on line 1—1 of Fig. 2, of the preferred form of the processing apparatus or tank;

Fig. 2 is a plan view of the apparatus of Fig. 1 with parts broken away and shown in section;

Fig. 3 is a fragmentary elevational view looking from the right of Fig. 1 and drawn to a smaller scale;

Fig. 4 is a fragmentary vertical section taken on the line 4—4 of Fig. 2;

Fig. 5 is a view in side elevation of a modified form of processing tank with parts broken away and shown in central vertical section;

Fig. 6 is a view in central vertical section of another modification;

Fig. 7 is a similar view of a further modification; and

Fig. 8 is a similar view of still another modification.

2

Referring now to the accompanying drawings, the preferred form of the processing or developing tank is constructed to have an inner processing or developing chamber 1 having cylindrical side walls 5 2 extending upwardly from a bottom wall 3. Surrounding and spaced from cylindrical walls 2 are the concentric outer cylindrical walls 4, also extending upwardly from bottom member 3 and forming an annular chamber 5 surrounding the 10 processing chamber 1.

Extending upwardly from bottom member 3 and fixed in a central boss 6 on the inner surface thereof, is a stationary vertical shaft or arbor 7, the upper end of which is not far below the top 15 of the cylindrical walls 2 of developing chamber 1. The negative holder, indicated generally by numeral 8, and in this instance comprising a reel for roll or strip film, is arranged to turn freely on shaft 7.

20 The negative holder or film reel 8 may be of any suitable construction and as shown in Fig. 1 comprises a spindle 9 having an axial hole to receive shaft 7 on which the spindle freely turns. Near the lower end of spindle 9 is the lower reel end or head 10 which may be formed integrally therewith, as indicated, or if desired may be adjustably positioned thereon in any suitable manner after common practice. Farther up on spindle 9 the top reel head or disk 11 is mounted. In the preferred arrangement the lower reel head 10 is 25 fixed in position on spindle 9 and the top reel head 11 is adjustably positioned thereon in any suitable manner so that the spacing between the two heads may be changed to accommodate different widths of film strip. The lowermost position of upper reel head 11 is shown by the three parallel dot and dash lines just below the middle 30 of the reel.

It will be understood that these two reel heads are provided with spiral channels, as is customary, and that the opposite marginal edges of the film 35 12 are threaded into these channels so that the film strip is held in position in a plurality of convolutions slightly spaced apart from one another at all points, the film having, in the drawings, the appearance of a cylinder extending between the lower and upper reel heads 10 and 11.

The outer walls 4 of annular chamber 5 extend upwardly somewhat above the top of the inner cylindrical walls 2 of developing chamber 1 and 40 within this space is mounted an impeller wheel or disk 13 which is arranged to turn the spindle 9. For this purpose the upper end of spindle 9 is reduced somewhat in diameter, forming a shoulder 14, and this upper reduced portion is slabbed 45 55 as indicated at 15 in Fig. 2, and the aperture

through hub 16 of impeller 13 is shaped to fit this flat-sided extension of the spindle, the parts having an easy sliding fit so that the impeller wheel may be readily slipped onto or removed from the top of the spindle.

Impeller member 13 is preferably a continuous disk which substantially fills the cylindrical space within the outer walls 4 with just enough clearance provided to allow for free rotation. The impeller blades 17 project downwardly from the lower surface of the peripheral margin of impeller 13 wholly within the annular temperature control space 5, so that water directed against these blades will be collected within such annular space and prevented from admission to the processing chamber 1.

A stream of water under suitable pressure to play against blades 17 and cause rotation of the impeller 13 and consequently spindle 9 and film 12 is supplied by means of a nozzle 18 under the control of a hand valve 19. This water is supplied under a controlled temperature through a flexible tubing 20 which may conveniently be connected to a hot and cold water mixing faucet for the purpose of temperature control. It will be understood that a thermostatic mixing valve may be used, if desired, in order to control the temperature within close limits.

The water under such controlled temperature, after driving the impeller disk 13, forms a temperature controlling bath in the annular temperature control space 5, the level of this bath being fixed by means of an outlet 21 shown at the left in Figs. 1 and 2. A flexible tubing may be applied to this outlet for convenient disposal of the overflow.

For the purpose of filling processing chamber 1 with the desired treatment solution, a conical filling spout 22, within which the lower end of a funnel 23 may be conveniently received is provided. Spout 22 communicates with a channel 24 extending vertically along one side of outer cylindrical walls 4 to the bottom 3 of the device, where it communicates through a horizontal passage 25 with the interior of chamber 1.

The outer wall of vertical channel 24 may be provided with a transparent window 26 (Figs. 1 and 3) through which the level of the solution may be observed. A suitable scale 27 may be provided which may be conveniently graduated according to the film number, so that when a film of a given size is to be processed the chamber 1 will be filled to the level corresponding to that number.

A suitable overflow outlet 28 from processing chamber 1 may be provided. When it is desired to drain chamber 1 of the treatment solution this may be accomplished by means of an outlet valve 29 at the bottom of channel 24 opposite cross-passage 25.

While the impeller disk 13 serves as a partial light excluding cover for the processing chamber 1, this chamber is preferably provided with a cover member 30 which fits closely the periphery of cylindrical walls 2. Cover 30 is provided with a light trap surrounding spindle 9 comprising the spaced telescoping sleeves 31 and 32, the latter sleeve being mounted on a member to be described below.

In order to avoid streaking of the film which might be occasioned by a continuous circular movement of agitation of the film with respect to the treatment solution, and to avoid setting up a continuous circular movement of the solution in sympathy with a continuous circular move-

ment of the reel, and continually to bring a given point on the film in contact with a different part of the solution, provision is made for an axial motion of the film reel simultaneously with the circular motion. This is accomplished by means of a cam 33 below the lower reel head 10 which coacts with a stationary abutment member 34 shown in the form of a rod threaded into boss 6 adjacent shaft 7. As the reel 8 rotates it is shifted from the full-line position to the position indicated by the dot-and-dash lines during each complete revolution. The member on which cam 33 is formed is fixed to the lower end of spindle 9 and, as indicated, may be made integral with the lower reel head 10.

The impeller 13 being carried on shoulder 14 of spindle 9 has an up and down movement with the reel 8. The impeller vanes 17 are of sufficient length so that they will not move out of the influence of the jet or nozzle 18 during this up and down movement.

Impeller 13 is used to rotate reel 8 only during the processing of the film with the various treatment solutions such as the developing bath, the acid step bath, and the fixing or hardening bath, or, in other words, up to the point of washing the film free of all traces of chemical solution which usually requires the longest period of time. In order to conserve water a second impeller is provided inside of the inner chamber 1. This second impeller comprises an impeller disk 35 having on its upper surface a series of spaced impeller ribs 36, the disk being fixed in any suitable manner as, for example, by means of a force fit, on spindle 9 just above the upper reel head 11. Impeller disk 35 is thus permanently fixed in position on spindle 9 while reel head 11 may be adjusted downwardly as may be required to support the narrower sizes of film.

A second water nozzle 37 (Fig. 4) is directed downwardly at an angle so as to carry the stream against the sides of the impeller ribs 36 at all the positions of the impeller disk in its up and down movement under the action of cam 33. A valve 38 is provided to control the flow of water through nozzle 37 and the water, after impinging on the impeller ribs 36 collects in chamber 1, valve 29 being closed, up to the level of outlet 28 which maintains the height of the water bath above the top of the upper edge of the film but at such a level that the impeller ribs 36 operate substantially at or above the water level at all times. Sleeve 32 which cooperates with sleeve 31 to form a light trap for the cover 30 around the spindle may be made integral with disk 35 as indicated in Fig. 1. It is to be noted that these two sleeves are of sufficient length to permit the up and down movement of the rotating parts above referred to and caused by cam 33.

In the modified form of the improved processing tank shown in Fig. 5, only a single impeller member, the impeller disk 13a is used, and there is also no up and down movement of the negative holder 8a, the cam 33 of the form shown in Fig. 1 being omitted. In other words, this modification provides a somewhat simplified form of the invention.

Inasmuch as the second or inner impeller disk is omitted, the sleeve 32a of the light trap is provided with a collar portion 39 of reduced diameter in order to secure the part in place on spindle 9a by means of a set screw 40.

Since there is no up and down movement of spindle 9a and its associated parts including negative holder 8a, the impeller blades 17a are

shorter in length, also the long stationary shaft of Fig. 1 is omitted and in place thereof a short pintle 41 is arranged preferably as an integral projection from the bottom wall 3a of the tank. Pintle 41 engages in a short axial recess 42 in the lower end of spindle 9a. As shown in Fig. 5, the lower reel head 10a of film holder 8a is shown as also being made integrally with the lower end of the spindle.

In using this form of processing tank, the manipulation is much the same as with the preferred form shown in Fig. 1, that is to say, the various treatment solutions are admitted to and removed from the inner processing chamber 1a in precisely the same way as in the case of chamber 1. The difference in operation is that there is no up and down agitating movement, but only a circular movement of the film reel or holder 8a.

It will be understood that the developing tank shown in Fig. 5 is provided with nozzles 36 and 37 just as is the tank of Fig. 1. The opening of nozzle 37, however, can be enlarged, if desired, as it serves only the purpose of admitting water for washing purposes into the chamber 1a. The admission of this water is controlled by valve 38, and valve 19 is manipulated to control the speed of rotation of the impeller disk 13a which is used to rotate the film reel 8a during the washing operation as well as during the treatment of the film with the various chemical solutions. In this form of processing tank, the water from the impeller which is collected in the outer or concentric chamber 5 serves to control the temperature of the developing bath and other treatment baths in the same way as in the case of the tank shown in Fig. 1.

Referring now to Figs. 6, 7 and 8, three different forms of further simplified processing tanks embodying some but not all of the desirable features of the tank of Fig. 1 are shown. The modification of Fig. 6 is a form of developing tank which may be operated manually, or by an external source of power, whereas the form shown in Fig. 7 is manually operated during the developing and fixing of the negative, but automatically agitated during washing, and Fig. 8 shows a modification intended for washing only.

In Fig. 6, the processing tank comprises a bottom wall 43 and cylindrical side walls 44 which are closed at the top by means of a cover 45. The cover embodies a light trap 46 around its periphery comprising a pair of spaced annular flanges, the inner one of which is received loosely within a groove 47 in the top of the tank, and two pouring slots 48 are provided at diametrically opposite parts of the cover through which the treatment solutions may be drained from the interior of the tank, air entering through one while the liquid flows out through the other.

Cover 45 is provided with the usual funnel surface 49 surrounding spindle 50 for introducing the liquid. Also, it has a light trap around the funnel neck composed of two spaced annular flanges 52 that coact with a pair of spaced annular flanges 53 which project upwardly from a disk 54 attached to spindle 50 inside the cover. The inner annular flange 53 is provided with liquid passages 55 which are angularly displaced from similar passages 56 in the outer flange 53. Thus the cover construction embodies a device to allow the treatment solutions to be introduced into the developing tank after the cover is in place.

The negative holder or film reel 8b is similar to

the negative holder 8 except for a change in the cam device for causing the up and down agitating movement of the reel. It comprises a lower reel head 10a and an upper reel head 11a, the lower reel head being fixed to the lower end of spindle 50 and the upper reel head being shiftable in position thereon so as to accommodate film strips of different width. In the position shown, the upper reel head 11a is adjusted to receive the maximum width of film.

Spindle 50 has a central axial opening to receive a stationary shaft 7a which may be mounted in base member 43 in much the same way as shaft 7 in Fig. 1. Instead of cam 33 being mounted on the spindle or on the lower reel head as in Fig. 1, however, a cam disk 57 is secured in fixed position on stationary shaft 7a, and a support 58 in the form of a projection from the lower surface of the spindle and lower reel head assembly engages the cam disk. Consequently, when the spindle is rotated, the film on the reel will be given a compound agitating movement, that is, both a circular and an up and down movement. Rotation may be imparted to spindle 50 by an outside source of power in any convenient manner, such, for example, as by a pulley 51 forced onto the knurled upper end of the spindle and a belt 51' which may be driven by an electric, or other, motor. Also pulley 51 may be removed and spindle 50 rotated by grasping the knurling with the fingers.

In the modification shown in Fig. 7, the construction is exactly as described in connection with Fig. 6 except that the upper reel head 11b is provided with impeller ribs 59 which are similar to ribs 36 of the second impeller disk 35, and provision is made for supplying a stream of water under pressure against these ribs during the washing operation, and for maintaining the level of the water at the proper height with respect to the film and these impeller ribs.

The impelling stream of water is supplied through a flexible tube 60 to a nozzle member 61 having a control valve 62 and a nozzle tip 63. Nozzle member 61 is pivotally mounted in a recess in the side wall of the tank above the liquid level, being frictionally held in adjusted position in this recess by means of a plate 76 which may be secured in place by suitable screws. Nozzle tip 63 delivers its jet through an aperture in the tank wall. By taking hold of the outer part of nozzle member 61 with the fingers, the nozzle can be shifted on its pivot to change the angle at which the stream is directed against the impeller ribs 59. Thus when reel head 11b is in the position shown in full lines in Fig. 7 in order to accommodate the maximum width of film, nozzle tip 63 will be adjusted to its full line position. However, when the reel head 11b is moved downwardly on spindle 50, for example to the dotted line position indicated in Fig. 7 so that the reel may accommodate a considerably narrower film, nozzle 63 will be adjusted to about the position shown in dotted lines. Thus the nozzle may be adjusted to direct an effective stream against the impeller ribs under all conditions. The change in level of the ribs during the up and down movement imparted by cam 57 will not substantially affect rotation. Also, it will be understood that the flanges 52 and 53 which form the light traps around the spindle 50 in both Figs. 6 and 7 are of sufficient length in a direction parallel to the axis of the spindle to permit this up and down movement.

Inasmuch as it is necessary, in order to pro-

vide proper rotation of the film reel by the jet of water acting upon the impeller ribs 59, to adjust the level of the water washing bath so that it is above the edge of the film but not substantially above the impeller ribs 59, a device is provided for changing the level of the water bath with change in the width of the film undergoing treatment. For this purpose, the form of the tank shown in Fig. 7 is provided with an outlet connection 64 at the bottom having an outlet valve 65 which may be connected to the drain by means of a flexible tube or otherwise. Also connected to outlet 64 is an upright tube 66 which extends about half way up the side of the tank. Fitting over tube 66 is an adjustable sleeve 67.

Valve 65 is intended primarily for draining the developing, fixing and other treatment solutions from the tank, and during this part of the processing of the film sleeve 67 will be adjusted to a position somewhat above that shown in Fig. 7 in order to prevent overflow of solution from the upper end of the sleeve. Whenever it is desired to carry on the operation of washing the film, sleeve 67 is adjusted to the position of Fig. 7, valve 65 is closed and the water overflows from the upper end of sleeve 67 thereby maintaining the bath at the desired level for washing the maximum width film. When narrower films are being washed, sleeve 67 is lowered correspondingly.

It will be understood that the film reel of the device of Fig. 7 may, if desired, be rotated during developing, fixing and washing, by an external source of power as described in connection with Fig. 6, the wash water being preferably introduced through the funnel opening in the top.

In the modification of Fig. 8, a washing tank has been provided in which the agitation is accomplished automatically. It consists of a simple cylindrical container 68 closed at the top with a cover 69. A spindle 70 supports lower and upper reel heads 10c and 11c respectively, these being adjustable thereon to support different width film. Above reel head 11c and fixed in position on spindle 70 is an impeller disk 71 having impeller ribs 72 on its upper surface. This impeller is not unlike impeller 35 of Fig. 1. A nozzle 73 is mounted in the side wall of tank 68 at an appropriate angle to discharge a stream of water under pressure against ribs 72. Nozzle 73 is fixed instead of being adjustable like nozzle 63 since the position of impeller disk 71 is independent of the adjustment of reel head 11c.

The lower end of spindle 70 is received in a bearing recess 74 provided in a boss formed in the bottom of tank 68. The upper end of spindle 70 projects above impeller disk 71 just enough to serve as a handle in lifting out the film reel. A discharge outlet tube 75 is arranged in the side of tank 68, the wash water overflowing from the top of this tube, which maintains the water level within the tank. It is not adjustable as the same water level is maintained regardless of the width of film being washed.

By means of our invention, there has been provided a form of processing tank which eliminates the tediousness from the work of developing, fixing and washing of photographic negatives. The improved tank also provides for better temperature control and better agitation of the negative undergoing treatment, bringing all portions thereof continuously into contact with fresh solution or wash water. At the same time, the improved construction is not complicated but on the other hand is simple, is not expensive

to manufacture and is convenient to use, resulting in quicker and more thorough development, fixing and washing.

It will be understood that various constructional changes in the apparatus described above, and various combinations of parts, may be made within the scope of the invention. For example, the stationary form of cam shown in Figs. 6 and 7 for producing the rise and fall movement of the rotating negative holder can be used in Fig. 1 in place of rotating cam 33 and abutment member 34; also, this type of cam may be used in the device of Figs. 6 and 7. If desired, the reel head 11c of Fig. 7 with its impeller ribs 59 may be used in the processing tank of Fig. 1 replacing reel head 11 and impeller disk 35. In that event, an adjustable nozzle 63 would also replace fixed nozzle 18. Similar changes can be made in the washing tank of Fig. 8, utilizing the reel head 11b with its integral impeller ribs 59, thus eliminating the necessity for a separate impeller disk as shown in Fig. 8 and described above. With this change, the adjustment of the film reel for different widths of film is accomplished by moving the lower reel head 10c upwardly for narrower widths of film than that illustrated in Fig. 8. It will be understood that other changes may also be made in the several embodiments without departing from the spirit of the invention or without exceeding the scope of the appended claims.

We claim:

1. A photographic negative processing apparatus comprising a receptacle having an inner processing chamber to contain a liquid treatment bath and an outer chamber surrounding the same, a rotatable negative holder, means for supporting said holder for rotation within said processing chamber, an impeller wheel operative to rotate said holder having blades disposed within said outer chamber, and a nozzle for directing a jet of water against said blades.

2. A photographic negative processing apparatus comprising a receptacle having a bottom and spaced side walls forming a cylindrical processing chamber to contain a liquid treatment bath and an outer chamber surrounding the same, a rotatable negative holder, means for supporting said holder for rotation about a vertical axis within said processing chamber, an impeller wheel operative to rotate said holder having blades disposed within said outer chamber, and a nozzle for directing a jet of water against said blades.

3. A photographic negative processing apparatus comprising a receptacle having an inner processing chamber to contain a liquid treatment bath and an outer chamber surrounding the same, a rotatable negative holder, means for supporting said holder for rotation about a vertical axis within said processing chamber, an impeller wheel operative to rotate said holder having blades disposed within said outer chamber, a nozzle for directing a jet of water against said blades, said water collecting in said outer chamber, whereby the same water serves first to rotate said holder and afterward to supply a temperature controlling bath for the liquid in said processing chamber.

4. In a photograph negative processing apparatus, a receptacle containing a liquid treatment bath, a removable cover member for said receptacle, a negative holder, a spindle for rotatably supporting said holder within said receptacle, one end of said spindle extending through said cover, means for producing axial movement of said

holder during rotation thereof to bring the surface of the negative in said holder continuously into contact with different portions of said bath liquid, said cover member having an aperture therein for said spindle, an impeller disk secured to said spindle above said cover member, and a cylindrical skirt projecting from said disk and surrounding the upper edge portion of said receptacle and cooperating therewith at all positions of said spindle to exclude light from the interior of said receptacle.

5. In a photograph negative processing apparatus, a receptacle to contain a liquid treatment bath, a vertically extending spindle mounted for rotation therein, a negative holder comprising an upper negative support mounted for vertical adjustment along said spindle, a lower negative support fixed to said spindle, said supports being adapted to receive different sized negatives therebetween and being rotatable with said spindle in said receptacle, impeller means for rotating said spindle fixed thereto above the uppermost position of said adjustable support, and a nozzle associated with said receptacle to direct a jet of liquid against said impeller means, said jet being unimpeded by surrounding liquid.

6. In a photographic negative processing apparatus, a receptacle adapted to contain a liquid treating bath, a vertically-extending spindle mounted for rotation therein, negative-holding means carried by said spindle and spaced vertically thereon to maintain a negative in vertical position in the receptacle for treatment by a liquid treating bath therein, at least one of said negative-holding means being non-rotatively connected to the spindle, an outlet from said receptacle for maintaining a liquid treating bath at a predetermined level in said receptacle, impeller means mounted on the spindle and non-rotatively connected thereto, whereby rotation of the impeller means causes rotation of the spindle and the negative-holding means non-rotatively connected thereto, and a nozzle carried by the receptacle to direct a jet of liquid against the impeller means, said impeller means and the nozzle both being above the predetermined level of the bath in the receptacle, whereby the liquid bath in the receptacle does not interfere with a jet of liquid from said nozzle being directed against the impeller means.

7. In a photographic negative processing apparatus, a receptacle adapted to contain a liquid treating bath, a vertically-extending spindle mounted for rotation therein, negative-holding means carried by said spindle and spaced vertically thereon to maintain a negative in vertical position in the receptacle for treatment by a liquid treating bath therein, at least one of said negative-holding means being non-rotatively connected to the spindle, an outlet from said receptacle for maintaining a liquid treating bath at a predetermined level in said receptacle, impeller means mounted on the spindle and non-rotatively connected thereto, whereby rotation of the impeller means causes rotation of the spindle and the negative-holding means non-rotatively connected thereto, a nozzle carried by the receptacle to direct a jet of liquid against the impeller means, said impeller means and the nozzle both being above the predetermined level of the bath in the receptacle, whereby the liquid bath in the receptacle does not interfere with a jet of liquid from said nozzle being directed against the impeller means, and means to recip-

rotate the negative holding means simultaneously with the rotation thereof.

8. In a photographic negative processing apparatus, a receptacle adapted to contain a liquid treating bath, a vertically-extending spindle mounted for rotation in the receptacle, a pair of negative supports mounted on the spindle and relatively adjustable to one another thereon to receive the opposite marginal edges of negatives of different widths, impeller means on the spindle and secured thereto independently of the negative supports, whereby the negative supports may be adjusted relative to one another longitudinally of the spindle without affecting the position of the impeller on the spindle, and a nozzle carried by the receptacle in a position to direct a jet of water against the impeller to cause rotation thereof and the spindle and negative holders mounted thereon.

15 9. In a photographic negative processing apparatus, a receptacle adapted to contain a liquid treating bath, a vertically-extending spindle mounted for rotation therein, a negative holder comprising upper and lower negative supports mounted in relatively adjustable position on the spindle to receive negatives of different sizes between them, impeller means carried at the upper side of the upper negative support, an overflow outlet for said receptacle at a level to maintain the treatment bath therein below said impeller means and at least as high as negatives carried by the negative holder, and a nozzle carried by the receptacle to direct a stream of liquid against the impeller means.

30 10. In a photographic negative processing apparatus, a receptacle adapted to contain a liquid treatment bath, a vertically-extending spindle mounted for rotation therein, a negative holder comprising a lower negative support secured to

40 the spindle, an upper negative support carried by the spindle and adjustable therealong, whereby the space between the upper and lower negative supports may be varied to receive negatives of different sizes between them, said negative supports being rotatable with the spindle in the receptacle, impeller means mounted on the spindle and positioned at least as high as the upper side of the upper negative support, a nozzle carried by the receptacle to direct a jet of liquid against said impeller means, and an overflow outlet for said receptacle adjustable to substantially the level of the top of a negative in the negative holder to maintain the level of the treatment bath in the receptacle above such negative and below the impeller.

45 11. A photographic negative processing apparatus comprising a receptacle having an inner processing chamber to contain a liquid treatment bath and an outer chamber surrounding the same, a rotatable negative holder, means for supporting said holder for rotation about a vertical axis within the processing chamber, an impeller wheel operative to rotate said holder having blades disposed within the outer chamber, a second impeller means mounted for rotation with the holder within the processing chamber, and a nozzle carried by the outer chamber for directing a stream of water against the blades of said first impeller and a second nozzle carried by the inner chamber for directing a jet against the second impeller means, whereby the same water may be used to rotate the holder and to wash a negative carried by the negative holder.

55 12. In a photographic negative processing apparatus, a receptacle adapted to contain a liquid

treatment bath, an outlet for maintaining a predetermined level of liquid within the receptacle, a vertically-extending spindle mounted for rotation within the receptacle, a negative holder comprising a lower negative support fixed to said spindle and an upper negative support mounted for vertical adjustment along said spindle to vary the spacing between said supports for receiving negatives of different sizes between them, said negative supports being rotatable with the spindle in the receptacle, impeller means for rotating the spindle secured thereto above the uppermost position of the adjustable upper support, and a nozzle mounted within the receptacle to direct a jet of liquid against the impeller means, both the impeller means and the jet being at a level above the highest predetermined level of liquid bath in the receptacle, whereby the liquid bath in the receptacle does not interfere with the jet from the nozzle being directed against the impeller means.
